UNITED STATES PATENT OFFICE

145,532

DESIGN FOR A TOY BOAT

Samuel Orkin, Los Angeles, Calif., assignor to Harvey Machine Co., Inc., Los Angeles, Calif., a corporation of California

Application August 6, 1945, Serial No. 121,255

Term of patent 7 years

(Cl. D34—15)

To all whom it may concern:

Be it known that I, Samuel Orkin, a citizen of the United States, residing in the city of Los Angeles, county of Los Angeles, and State of California, have invented a new, original, and ornamental Design for a Toy Boat, of which the following is a specification, reference being had to the accompanying drawing, forming a part thereof.

The single figure is a perspective view of the toy boat showing my new design.

I claim:

The ornamental design for a toy boat, as shown.

SAMUEL ORKIN.
